GOOGLES

Emil B. Meyrowitz, New York, N. Y., assignor to
E. B. Meyrowitz, Inc., a corporation of New
York

Application January 15, 1930, Serial No. 420,830

7 Claims. (Cl. 2—14)

This invention relates especially to goggles for use where high wind pressure is encountered, as is the case, for example, with aviators. A cushion is ordinarily provided about the rear edge of the eyecups of such goggles to protect the face of the wearer, and some means are also provided to ventilate the eyecups so as to prevent fogging of the lenses.

While the cushions should of course be held securely to the eyecups, it is desirable that they be easily and quickly replaceable and that their mode of detachment in no wise interfere with the ventilation and with other functions of the eyecup.

In accordance with my invention, I lock the lip of the cushion within the rim of the eyecup by means of an inner reinforcing band which is preferably secured to the inner face of the lip and by reason of the relative configuration of the eyecup and rim positively locks the lip in the eyecup so long as the parts are in their normal or usable shape. Either the band or the eyecup, however, are resiliently deformable so as to permit of detachment. At the same time the band serves as a deflector to direct the air entering the ventilator toward the lens and away from the eye of the wearer.

In one form, for example, in which the eyecup is an endless band and the lens is held in place by a telescopic cover, the reinforcing band is deformable, and the band and eyecup have complementary recesses and detents which interlock and which may be released by springing the band. In the case of an eyecup which opens at the temple end and so is expanded to receive the lens and the cushion lip, the rim of the eyecup and the reinforcing band may be shaped so as mutually to overhang circumferentially and prevent axial separation or insertion until the eyecup is opened. For instance, they may both flare outwardly away from the rear sufficiently to afford a positive lock.

The security of this interlock may be enhanced by placing the loop or eye member to which the head band is attached, on the reinforcing band and having it protrude through the cushion lip and through an opening in the temple end of the eyecup. This may be done in the case of an eyecup which is split to open at the temple end, by bifurcating the overlapping ends sufficiently to leave an opening when the eyecup is clasped.

This form of cushion securing means may be adapted to cooperate with the usual ventilating devices in which the inlet and outlet ventilation

openings are in opposite sides of the eyecup. The inlet opening is usually in the bottom wall of the eyecup and the general width of the lip and reinforcing band at this point is such that they would cover the inlet opening. The lip, however, is cut away opposite the inlet opening so as to leave the band opposing the opening and spaced from it by the thickness of the lip. The incoming air, therefore, strikes the band and is deflected toward the lens. This deflecting action may be improved by bending the deflecting portion of the band slightly inwardly away from the cushion lip, which may readily be done by slitting the band inwardly a short distance from its edge and turning in the slotted portion. At the outlet ventilating opening, the lip and the reinforcing band are made sufficiently narrow to stop short of this opening and leave it entirely uncovered. It will be noted that this ventilating feature of the structure does not interfere at all with the interlocking feature.

Other detailed respects in which my invention improves upon prior devices of this sort will appear from the following description of certain embodiments of my invention which I have selected for the purpose of illustration.

Fig. 1 is an elevation of one goggle element of a pair of goggles embodying my invention, as viewed from the outer side;

Fig. 2 is a horizontal section of the same, on line 2—2 of Fig. 1;

Fig. 3 is a detail in corresponding elevation of the cushion member including the reinforcing band;

Fig. 4 is a sectional detail of the goggle element on line 4—4 of Fig. 1;

Fig. 5 is a sectional detail of the same on line 5—5 of Fig. 1;

Fig. 6 is a section detail of the same on line 6—6 of Fig. 2;

Fig. 7 is a fragmentary end elevation of the same at the temple end;

Fig. 8 is an elevation of a single goggle member constituting a modified embodiment of my invention, this illustration showing the member as viewed from the inner or face-engaging side with the cushion member sectioned at its junction with the lip and its outline indicated in dot and dash lines;

Fig. 9 is a longitudinal section of the same on line 9—9 of Fig. 8;

Fig. 10 is a detail in elevation of the cushion member of this modified form;

Fig. 11 is a fragmentary end elevation at the temple end of the structure shown in Fig. 8;

Fig. 12 is a circumferential section of the parts shown in Fig. 11;

Fig. 13 is a detail in perspective of the end portions of the eyecup of Fig. 8 in open position;

5 Fig. 14 is a view corresponding to Fig. 13, illustrating the structure modified by locating the head band attachment eye member upon the eyecup instead of upon the reinforcing band.

The structure shown in Figs. 1 to 7, inclusive, 10 is what may be termed the closed eyecup construction in that the eyecup is not split at the temple end but is an endless band. The eyecup 1 is an endless metallic band of oval outline with the lens 2 resting upon suitable supports 3 on the inner face of the eyecup. A lens cover ring 4 is hinged at the inner end of the eyecup and telescopes over the eyecup, having a narrow flange which overlies the edge of the lens and secures it in the eyecup. The usual 15 hinged clasp 5 on the outer or temple end of the cover ring engages over the head band loop in the usual way to hold the cover closed.

Fitting within the eyecup from its rear is the 20 lip 6a of the cushion member 6. This lip 6a is a circumferential axially extending lip of a size and shape to fit snugly within the eyecup rim. Within this lip 6a is a circumferential 25 reinforcing resilient metallic band 7 which is shown as secured to the lip by stitching. On 30 a line inwardly of the central vertical axis of the reinforcing band are two opposed detent members 8. These are shown as separate members riveted to the band. They extend above the outer edge of the lip and, in the assembled position of the parts, they engage in recesses 1a formed in the wall of the eyecup. The band 7 is sufficiently flexible to be easily deformable. Therefore, by springing the walls of the band together toward the inner end of the elliptical ring, 35 these detents may be brought together so as to release them from the recesses 1a.

At the temple end of the elliptical band, the band is provided with an outwardly projecting loop or eye 9 which serves for attachment of 40 the head band in the usual way. This loop 9 extends through a slit in the lip 6a and also through an opening in the band 1. It, therefore, serves as a third point of attachment of the band to the eyecup. The clasp 5 closes 45 over this loop or eye 9, as above mentioned.

To insert the cushion in the eyecup, one first 50 inserts the eye 9 through the opening in the eyecup and then springs the wall of the band and the lip together toward the opposite end and pushes the lip into the eyecup until the detents engage in the recess 1a. The lip is thus 55 securely locked in the eyecup. To remove the cushion, it is only necessary to reverse the operation, first deforming the band so as to disengage the detents 8 from the recesses 1a and withdrawing that end of the cushion, and lastly, withdrawing the eye member 9 from the eyecup.

To ventilate the space back of the lens so as to 60 prevent fogging, the eyecup is shown as having well known ventilating means. The air inlet is at the bottom of the eyecup and the outlet is at the top. The inlet consists of a series of circumferentially spaced holes 10. The flange of the 65 cover 4 which telescopes over the eyecup has a series of holes 11 which register with the holes 10 when the cover is closed. Air is directed toward the inlet openings by a baffle member 12 which is arch-shaped in cross section with closed ends 70 and is secured on the eyecup wall over the inlet 75

openings and is provided along its front face with a series of openings 13. As the wearer of the goggle moves forward, the air is therefore caught by the openings 13 and is directed by the baffle into the openings 10 and 11.

The lip 6a is cut away at its outer edge over the circumferential distance occupied by the inlet openings 10 so as to leave these openings uncovered on the inside of the eyecup. This appears quite clearly from Fig. 4. The band 7, 10 however, extends with its outer edge above the cut away portion of the lip and in front of the inlet openings and serves to direct the incoming air toward the lens. As shown in Fig. 4, this deflector portion of the band may be turned inwardly so as more effectively to deflect the air toward the lens, and for this purpose the band is slotted on opposite sides of the deflector portion. In the top wall of the eyecup there is formed a circumferentially extending outlet portion 14, and 15 the flange of the cover member 4 which embraces the eyecup has a corresponding opening 15 which registers with the opening 14. An arch-shaped baffle member 16, provided with a longitudinal series of outlet openings may also be secured on 20 the cover member over the openings 15.

In Figs. 8 to 13, inclusive, I have shown my invention applied to a so-called open eyecup, that is, one which is split at the temple end and opens up at this joint to admit and release the lens and 30 the cushion. The illustrated eyecup is generally of the form disclosed in my copending application Serial No. 337,559, filed February 5, 1929. The wall 17 of the eyecup flares outwardly from its inner side and has a V-shaped bezzle 17a at its 35 outer edge for the reception of the lens. The lip 18a of the cushion 18 is similarly flared, as is the reinforcing band 19, which is secured about the inner face of the lip, as by stitching. When the eyecup is opened up, the flared lip with its 40 reinforcing band may be inserted in place in the eyecup, and the closing of the eyecup then serves to lock the cushion and reinforcing band positively within the eyecup by reason of the overhang of the parts. Furthermore, the band 19 45 may, as shown in these figures, have the head band engaging loop or eye 9 on its temple end. The overlapping ends of the eyecup are bifurcated and the length of these bifurcations is such that when the eyecup is closed, an opening is left 50 for the loop 9. This appears clearly in Figs. 11, 12 and 13. A hinged latch member 20 on one end section has an opening in it sufficiently long to receive the loop 9 and to latch over a catch 21 on the opposing end section.

As shown in Fig. 14, it is not essential to the invention that the loop 9 be on the band 19 since the lip with its reinforcing band will be locked positively in the eyecup by the overhang due to the flare of the eyecup and enclosed members. 60 Therefore, the loop or eye member 9a may be on one of the ends of the eyecup and serve as the catch for the latch member 20. In this case only the end which carries the latch member will be bifurcated so as to straddle the eye member 9a 65 when the eyecup is closed.

In either case the ventilating construction of the lip and reinforcing band of the cushion will be similar to that of the cushion member of Figs. 1 to 7, inclusive. The lip 18a will be cut out, as 70 shown in Fig. 10, at the point where it would otherwise cover the inlet openings, and the band 19 will be slotted and turned back opposite the ventilation openings so as to form a deflector member. This appears also clearly in Fig. 9. 75

The bearing for the leg of the bridge member 22 protrudes internally of the eyecup, and the lip 18a and the reinforcing band 19 are also cut away at this point to accommodate this bearing.

5 It is obvious that various modifications may be made in the constructions shown in the drawing and above particularly described within the principle and scope of my invention.

I claim:

10 1. In a goggle, in combination, an annular eyecup including a cushion receiving rim portion, an annular cushion having an axially extending circumferential attaching lip, and a metallic reinforcing annular band fitting interiorally of the lip and secured thereto, the lip fitting within the rim portion and the rim portion and band having complementary projections and recesses and one of them being deformable so as to permit insertion and removal of the lip.

20 2. In a goggle, in combination, an annular cushion having an axially extending circumferential attaching lip, a metallic reinforcing annular band fitting interiorally of the lip, and an eyecup fitting exteriorally about the lip, the said band and eyecup having complementary projections and recesses engaging together to lock the two parts against axial separation.

30 3. In a goggle, in combination, an annular cushion having an axially extending circumferential attaching lip, a metallic reinforcing annular band fitting interiorally of the lip and having at its temple end an outwardly extending eye member adapted to have passed therethrough the attaching piece of a head band, and an eyecup fitting exteriorally about the lip and having an opening through which the eye member protrudes.

40 4. In a goggle, in combination, an annular eyecup including a cushion receiving rim portion, an annular cushion having an axially extending circumferential attaching lip, and a metallic reinforcing annular band fitting interiorally of the lip and secured thereto, the band being deformable and having parts normally interlocking with

the rim portion to prevent axial separation of the cushion and eyecup and releasable from such interlocking by deformation of the band.

5 5. In a goggle, in combination, an annular eyecup including a cushion receiving rim portion, an annular cushion having an axially extending circumferential attaching lip, and a metallic reinforcing annular band fitting interiorally of the lip and secured thereto, the band being resiliently deformable and having at its 10 temple end an outwardly extending eye member for head band attachment and detents disposed inwardly of said eye member, said eye member extending through the eye cup rim and the detents normally interlocking with the said rim 15 and being releasable therefrom by deformation of the rim.

6. In a goggle, in combination, an annular eyecup member including a cushion receiving rim portion, an annular cushion having an 20 axially extending circumferential attaching lip, and a metallic reinforcing annular band member fitting interiorally of the lip and secured thereto, one of the members having locking depressions and the other member having locking 25 projections adapted to engage in the depressions when the lip is in the rim portion and the projections being resiliently yieldable to permit axial assembly and disassembly of the two members.

7. A goggle member comprising in combination, an eyecup of flexible material adapted to expand and contract in the plane thereof, the said eyecup flaring outwardly, a removable soft rubber cushion having an outwardly projecting lip extending into the eyecup, the said lip of the 30 cushion flaring outwardly in accordance with the flare of the eyecup, and a reinforcing backing band for the lip of the cushion engaging the inner surface thereof and adapted to press the lip of the cushion against the inner surface of 35 the eyecup, and means for locking the eyecup about the lip of the cushion.

EMIL B. MEYROWITZ.
